UNITED STATES PATENT OFFICE.

HENRY BERRY AND KEYES A. HATHAWAY, OF BIRMINGHAM, CONNECTICUT.

DESIGN FOR A TEA-POT.

SPECIFICATION forming part of Design No. 14,522, dated December 25, 1883.

Application filed November 7, 1883. Term of patent 7 years.

To all whom it may concern:

Be it known that we, HENRY BERRY and KEYES A. HATHAWAY, citizens of the United States, residing at Birmingham, in the county 5 of New Haven and State of Connecticut, have invented a new Design for Tea-Pot; and we do declare the following to be a full, clear, and exact description of the invention, such as will enable others skilled in the art to which 10 it appertains to make and use the same, reference being had to the accompanying drawing, and to letters or figures of reference marked thereon, which form a part of this specification.

15 The figure of the drawing is a representation of a perspective view of the tea-pot. The drawing represents a tea-pot. The body

of the tea-pot is ornamented on its exposed surface in conventional imitation of alligator-skin, the spout, handle, and top being of any 20 desired form, and decorated or plain.

What we claim, and desire to secure by Letters Patent, is—

The design for a tea-pot having a surface ornamentation of the body representing alligator-skin, as shown and described. 25

In testimony whereof we affix our signatures in presence of two witnesses.

HENRY BERRY.

KEYES A. HATHAWAY.
